APPARATUS AND METHOD OF CLEANING
TANKS CONTAINING FLUID

Peter M. Erdman, Los Angeles, Calif.

Application June 30, 1930, Serial No. 464,993

9 Claims. (Cl. 210—209)

My present invention relates to tank cleaning devices, and more particularly to devices for cleaning oil tanks and to a method of cleaning the same.

The objects of my invention are: first, to provide a tank cleaning device for tanks whereby the sediment or other foreign matter may be removed from the bottom of the tank without the necessity of emptying the same; second, to provide a tank cleaning device whereby the entire area on the bottom of the tank is cleaned at one time; third, to provide a tank cleaning device whereby the sediment may be removed or loosened from the bottom of the tank and placed in suspension before removing the same; fourth, to provide a tank cleaning device whereby a cleaning liquid may be forced over the bottom of the tank for loosening the sediment and washing the tank and then removing the liquid and sediment therefrom; fifth, to provide a tank cleaning device whereby a circular motion of the sediment is caused, thereby placing the same in suspension before its removal; sixth, to provide a tank cleaning device which may be readily installed, one which is simple and economical of construction, durable, and which will not readily deteriorate or get out of order; and, seventh, to provide a novel method of cleaning tanks.

With these and other objects in view as will appear hereinafter, my invention consists of a certain novel method of and of certain novel features of construction, combination and arrangement of parts and portions, as will be hereinafter described in detail and particularly set forth in the appended claims, reference being had to the accompanying drawing and to the characters of reference thereon which form a part of this application in which:

Figure 1 is a side elevation of my tank cleaning device positioned in a tank, showing the tank and certain portions of my device in section; Fig. 2 is a plan view of my device positioned in a tank for use, showing diagrammatically the suction pump and a supply pipe for cleaning fluid; and Fig. 3 is a sectional view of one of the nozzles and suction pipes taken at 3—3 of Fig. 2.

Like characters of reference refer to similar parts and portions throughout the views of the drawing.

My tank cleaning device consists in one form essentially of a central head or manifold 1 having a number of pipes 2 extending radially therefrom, supports 3 for supporting the pipes, and an elbow 4 connecting the head 1 through the tank 5 to a discharge pipe 6.

The head or manifold 1, in this instance, is supported on the bottom and in the center of the tank 5 by means of a flange 1a. The head 1 is provided with a large central opening 1b into which the pipes 2 discharge. To facilitate the securing of the pipes 2 to the head 1, the head 1 is provided with a number of flat sides to which flanges of the pipes 2 are secured and supported at their inner ends. Said pipes extend substantially radially outwardly therefrom, as shown best in Fig. 2. The pipes 2 are supported on the bottom of the tank at their outer ends by the supports 3, consisting of cross members provided at the ends with downwardly extending legs which rest on the bottom of the tank. Extending outwardly and downwardly from the pipes 2 are smaller or secondary pipes 2a. These pipes are flattened longitudinally at their outer ends to form nozzles 2b. The pipes 2 are bent at their ends at substantially right angles toward the side from which the pipes 2a project and are also flattened longitudinally forming nozzles 2c. All of the pipes 2a project at an angle from their respective main pipes and with the nozzles 2b directed to cause circular motion of the liquid in the tank. Thus, when suction is applied to the pipes, or when fluid is forced out of the nozzles, the liquid at the bottom of the tank is made to circulate in the tank.

The liquid from the head 1 is discharged through an opening 5a, in the bottom of the tank over which the flange 1a of the head 1 is secured, and out through the pipe 6 which is connected with the opening 5a by means of the elbow 4. The pipe 6 is connected to a T 7 which is in turn connected to valves 8 and 9, the valve 8 being connected to a suction pump 10 and the valve 9 to a liquid or steam supply pipe 11. The liquid contained in the tank, that is to be withdrawn for use, is withdrawn through the pipe 12 which is positioned above the pipes 2 and at the side of the tank 5.

Many fluids stored in tanks contain a great deal of foreign matter that remains in suspension as long as the fluid is agitated, but settles to the bottom of the tank in the form of sediment or scum when the liquid is allowed to remain at rest. With my device it is possible to remove such settled sediment or scum and other foreign matter from the bottom of the tank and then wash the bottom of the tank without removing any material part of the liquid contained therein.

When it is desired to clean the bottom of the tank the valve 8 is opened and the suction pump 10 started. Because the pipes 2a all extend in a

circular direction the liquid will be made to circulate about the bottom of the tank in a clockwise direction, when the pipes are arranged as shown. This circulation of the liquid agitates the sediment on the bottom of the tank and causes it to become loosened and suspended in the circulating liquid and consequently drawn out of the tank by means of the pump 10. After the larger part of the sediment is removed, the valve 8 is closed and the valve 9 opened allowing steam, water or other cleaning fluid to be forced into the tank through the nozzles 2b and 2c. In the case of oil tanks, steam is used since the heat of the steam dissolves and loosens the gummy oil more easily than would a liquid. This fluid will circulate in a counterclockwise direction or a direction opposite to that when being withdrawn. When the steam or other cleaning fluid has loosened the dirt and sediment and caused the same to become suspended, the valve 9 is closed and the valve 8 again opened, and the cleaning fluid thus withdrawn, removing any sediment or foreign matter with it. This process is repeated as many times as necessary to thoroughly clean the tank of sediment or other foreign matter.

Though I have shown and described a particular construction, combination and arrangement of parts and portions of my apparatus and certain steps of my method of cleaning tanks, I do not wish to be limited to this particular construction, combination and arrangement of parts and portions, nor to the particular method, but desire to include in the scope of my invention the construction, combination and arrangement of elements and the method substantially as set forth in the appended claims.

Having thus described my invention, what I claim as new and desire to secure by Letters Patent is:

40. 1. In a tank cleaning device, the combination with a tank, of a manifold positioned at the bottom of the tank, said manifold having a multiplicity of pipes extending substantially radially therefrom, said pipes having a multiplicity of openings, all of said openings opening in substantially the same general direction with respect to the side wall of said tank, a suction pipe, a fluid supply pipe, and means for connecting said manifold to either said suction pipe or said supply pipe.

45. 2. In a tank cleaning device, the combination with a tank, of a manifold positioned at the bottom of the tank, said manifold having a multiplicity of pipes extending substantially radially therefrom, said pipes having a multiplicity of openings, all of said openings opening in substantially the same general direction with respect to the side wall of said tank, a discharge pipe connected to the manifold and provided with 50. valve means for connecting the same to either a suction pump or a fluid supply pipe.

3. In a tank cleaning device, the combination with a tank, of nozzles arranged at the bottom thereof to cause a circular movement of liquid at the bottom of the tank by fluid discharged from the nozzles or fluid entering the same, suction

means connected to the nozzles, cleaning fluid supply means connected to the nozzles, and valves for controlling the flow of the contents of the tank to the suction means and from the supply means to the tank.

4. The herein described method of cleaning tanks containing fluid and having sediment on the bottom of the tank consisting in causing circular motion of the contents of the lower portion of the tank, thereby agitating the sediment, placing the same in suspension, and simultaneously removing the liquid with said sediment, then forcing a cleaning fluid into the bottom of the tank, thereby loosening the remaining sediment from the bottom of the tank, and then removing said cleaning fluid and sediment in suspension therein.

5. The herein described method of cleaning tanks containing fluid and having sediment on the bottom of the tank, consisting in causing a circular motion of the sediment by forcing a cleaning fluid into the bottom of the tank, the circular motion agitating sediment and placing the same in suspension, then reversing the direction of circulation by removing the fluid containing the suspended sediment.

6. The herein described method of cleaning oil and similar tanks containing a liquid and having gummy sediment at the bottom of the tank, consisting in forcing steam in a circular direction into the bottom portion of the tank for heating and loosening the gummy sediment and causing the same to swirl and to be placed in suspension, and then reversing the direction of circulation of the liquid at the bottom of the tank and the sediment in suspension therein by removing the portion of the liquid containing the suspended sediment.

7. The herein described method of cleaning oil and similar tanks containing a liquid and having gummy sediment at the bottom of the tank, consisting in forcing steam in a circular direction into the bottom portion of the tank for heating and loosening the gummy sediment and causing the same to swirl and to be placed in suspension, 110 and then removing the condensed steam and sediment by suction.

8. In a tank cleaning device, the combination with a tank, of nozzles arranged at the bottom thereof to cause a circular movement of liquid at the bottom of the tank by fluid discharged from the nozzle, discharge means connected to the nozzles, cleaning fluid supply means connected to the nozzles, and valves for controlling the flow of the contents of the tank to the discharge means, and from the supply means to the tank.

9. The method of cleaning oil and similar tanks containing a liquid and having gummy sediment at the bottom of the tank, consisting in forcing steam in a circular direction into the bottom portion of the tank for heating and loosening the gummy sediment and causing the same to swirl and be placed in suspension, and then removing the condensed steam and sediment.

PETER M. ERDMAN.
